UNITED STATES PATENT OFFICE.

CLINTON GUYER, OF MUNCY, PENNSYLVANIA, ASSIGNOR OF ONE-HALF TO WILLIAM C. CRAWFORD, OF MUNCY, PENNSYLVANIA.

FRICITION-REDUCING DEVICE FOR SLIDING DRAWERS, &c.

1,184,343.

Specification of Letters Patent.

Patented May 23, 1916.

Application filed February 15, 1916. Serial No. 78,457.

To all whom it may concern:

Be it known that I, CLINTON GUYER, a citizen of the United States, residing at Muncy, in the county of Lycoming and State 5 of Pennsylvania, have invented certain new and useful Improvements in Friction-Reducing Devices for Sliding Drawers, &c.; and I do hereby declare the following to be a full, clear, and exact description of the invention, such as will enable others skilled in 10 the art to which it appertains to make and use the same.

This invention relates to friction reducing devices for sliding drawers, shelves and the 15 like.

The primary object of the invention is to provide a simple, efficient and inexpensive device of the character referred to, adapted to eliminate friction or reduce to a minimum 20 frictional contact between sliding drawers or other slidable parts and their casings or housings, adapting them to be easily moved by means of either one or both handles with a noiseless smoothly running movement and 25 to facilitate the movement of the drawer or shelf when drawn out or shoved into proper position within the casing.

The invention will first be hereinafter more particularly described, with reference 30 to the accompanying drawings, which form a part of this specification, and then pointed out in the claims at the end of the description.

In said drawings, Figure 1 is a vertical 35 sectional elevation of a part of a cabinet or case of drawers, or the like, equipped with my improvement, showing one of a series of drawers in proper position within the casing; Fig. 2 is a fragmentary sectional elevation 40 of the same, the section being taken at right angles to the section shown in Fig. 1; Fig. 3 is a detail vertical sectional elevation on an enlarged scale, of one of the ball bearing devices detached, showing the ball in 45 full lines; the section being taken on the line 3—3 of Fig. 4; and Fig. 4 is a plan view on an enlarged scale of one of said ball bearing devices.

Referring to said drawings, in which the 50 same reference letters are used to denote corresponding parts in different views, the letter A may denote a sliding drawer of ordinary construction, in proper position within the casing or cabinet B, and provided 55 with ordinary handles or knobs for drawing

it out or shoving it into place. The cabinet B has formed in its bottom, at the front, and in the adjacent inner side wall thereof, or at each corner, near the front, one or more recesses or sockets b, which are preferably 60 cylindrical in form to adapt them to receive correspondingly-shaped cups C, in which are fitted balls D, which protrude slightly beyond the edges of the cup and are retained therein by indenting the edges of the cups, 65 as shown in Figs. 3 and 4. Similar sockets or recesses are also provided in the under-side of the bottom of the sliding drawer, at or near the rear end thereof, one or more at each side, and one or more in each of the 70 adjacent outer walls thereof and in the adjacent upper edges, as shown, so as to provide ball bearings at the front of the case or cabinet on the bottom and on the interior walls thereof and also at the rear end of the 75 sliding drawer, underneath its bottom, and on top, at each side, and on each outer wall or side. The top of the ball-holding and retaining cup is preferably substantially flush with the surface of the part in which it is seated, while the ball projects only slightly beyond said surface, so as to provide a rev- 80 oluble seat upon or against which the mov- able part may rest or abut and by means of which the drawer may be easily drawn out 85 or shoved in with a free and smooth running movement and without friction; friction being practically entirely eliminated or reduced to a minimum. The cups C may be stamped out of sheet metal, but are prefer- 90 ably constructed of steel, by simply boring or drilling a socket of the desired size for the ball in the end of a steel rod and round- 95 ing out the bottom of the socket so as to form a seat for the ball. The ball is then inserted and seated in the socket, and by indenting the edges of the cup, as at c, by means of a suitable tool, in the manner indicated in Fig. 4 of the drawings, the indented portion or portions will overlap the larger 100 diameter of the ball and prevent it from dropping out when the cup is inverted or turned bottom side up.

As will be observed, the form of the ball- 105 holding cup is such that the ball is firmly seated therein on its rounded bottom and retained by indentations at one or more points in the upper edge of the cup, (prefer- 110 ably at diametrically opposite points), which do not materially affect the cylindri-

cal form of the cup from top to bottom, so that it is adapted to fit snugly within and against the circular wall of a cylindrical socket its full length, thereby giving rigidity 5 and strength to the structure and adding materially to its efficiency as a friction reducing device of the character referred to.

It has heretofore been proposed to provide sliding drawers or the like with anti-friction devices, or means for reducing friction, and I therefore make no broad claim 10 to the application of anti-friction devices to such uses; but in prior constructions it is the common practice to use fastening devices of some sort which are liable to cause trouble and which are entirely eliminated by my improvement, in which no fastening means are required to secure the ball bearings 15 in place within the casing or on the sliding drawer or shelf, as the cups are adapted to fit snugly in the correspondingly shaped sockets, with sufficient friction to prevent them from being accidentally displaced or dropping out, and there are no 20 bolts or screws or other fastenings employed, which are liable to work loose or drop out and cause trouble.

My improved device eliminates the necessity for and dispenses entirely with extraneous retaining or securing means, such as retaining plates, screws, bolts, projections, or other fastenings, for securing either the balls or the ball holding and retaining cups in the desired position. In my device there 35 is simply a ball holding and retaining cup and a cup holding and retaining socket, without any additional appliances, strips, plates, screws or projections of any kind, which increase the expense and render the 40 device unsatisfactory in practical use, by reason of the fact that such extraneous appliances are liable to work loose and drop out or cause trouble and inconvenience of

some kind, which is not possible with my improvement. My improvement also has 45 the advantage of simplicity combined with strength and efficiency and inexpensiveness in manufacture.

Having thus described my invention, what I claim as new and desire to secure by Letters Patent of the United States is:

1. A friction reducing device including a movable and a stationary part, one of said parts having a cylindrical socket therein, and a ball holding and retaining cup of 55 cylindrical form seated in said socket; the outer cylindrical wall of said cup being substantially of uniform diameter from top to bottom, to adapt it to closely fit the interior wall of said cylindrical socket its full depth, 60 and having its mouth substantially flush with the socketed surface in which it is seated; said cup having a ball therein protruding slightly beyond its mouth in rolling contact with the other part and retained 65 by indentations in the edge of the cup.

2. In a friction reducing device of the character described, a ball holding and retaining cup of cylindrical form, its exterior wall being substantially of uniform diameter from top to bottom, to adapt it to closely fit the interior wall of a cylindrical socket the full length of the cup, and its interior diameter being substantially uniform from its mouth to its bottom, and its bottom being 75 rounded; said cup having a ball therein protruding slightly beyond its mouth and retained by indentations in the edge of the cup.

In testimony whereof I affix my signature in the presence of two witnesses.

CLINTON GUYER.
